(57) **CLAIM**

The ornamental design for an automotive tailgate, as shown and described.

DESCRIPTION

FIG. 1 is a rear end perspective view of a first embodiment automotive tailgate in accordance with the present invention;

FIG. 2 is a rear end perspective view of a second embodiment automotive tailgate in accordance with the present invention; and,

FIG. 3 is a left side/rear end perspective view of the automotive tailgate of FIG. 2, wherein the right side/rear end perspective view is a mirror image thereof.

The broken lines are for illustrative purposes only and form no part of the claimed design.
